UNITED STATES PATENT OFFICE

2,408,704

LIQUID COOLER FOR REFRIGERATORS

George R. Taylor, Kenosha, Wis.

Application May 4, 1944, Serial No. 534,172

1 Claim. (Cl. 62—89)

1

This invention appertains to liquid coolers for refrigerators and more particularly to a novel means for incorporating a liquid dispensing device in a wall of a common domestic refrigerator.

As is well known, the common practice for housewives is to place milk, fruit juices, water, and the like in bottles or jars and position the same inside of the refrigerator for cooling purposes.

This necessitates the continuous opening and closing of the door of the refrigerator to gain access to said bottles or jars; with the consequent admittance of warm air into the refrigerator and the exit of cold air from the refrigerator. This, naturally lessens the efficiency of the refrigerator and additional work is placed upon the refrigerating unit. Likewise, the bottles and jars have to be frequently handled and the danger of breakage is always a hazard, particularly where there are children in the household.

Some attempts have been made to build a liquid cooler in a refrigerator and all such attempts, with which I am familiar, are open to serious objection. Either, they are expensive or complicated to manufacture and incorporate in a refrigerator, or there are parts projecting from the refrigerator which catch in the garments of the housewife, or the effective insulating of the refrigerator is interfered with to too great an extent. Also in many instances, the flow of the liquid through long conduits or pipes is a necessity, which is liable to contaminate the liquid, particularly where milk is being dispensed.

It is therefore one of the primary objects of my invention to provide a liquid cooler and dispensing device for refrigerators, which can be easily incorporated therein at a small expense and which will be exceptionally durable and efficient in use.

Another salient objective of my invention is to provide a refrigerator having a liquid cooler built therein, which will have no projecting parts to collect dirt and dust and in which all parts are normally inclosed and concealed from view.

A further important object of my invention is to provide a refrigerator wall or door embodying the usual inner and outer shells with the insulation therebetween, the inner shell (according to my invention) having an instruck pocket or cavity for dispensing jars and the outer shell having a similar instruck pocket or cavity below the inner pocket for beverage glasses, the pockets having communicating openings for the necks of the jars, whereby said necks can extend into the low-

2

er pocket for the dispensing of the contents of the jars into the glasses.

A further salient object of my invention is to provide a quick removable dispensing valve or tap for the neck of each jar extending into the lower cavity, so that the same can be easily and quickly manipulated by the operator, the arrangement of valve and jar necks being such, that the travel of the liquid from the jar to the drinking glasses will be reduced to a minimum and so that the collection of liquid in the valves will be prevented.

A still further important object of my invention is to provide a closure for the outer pocket or recess, which will be substantially flush with the outer face of the refrigerator wall or door when such closure is in its closed position for preventing the entrance of dust and dirt in said outer pocket or recess and which, when in its open operative position, will form a serving shelf for the drinking glasses.

With these and other objects in view, the invention consists in the novel construction, arrangement and formation of parts, as will be hereinafter more specifically described, claimed and illustrated in the accompanying drawings, in which drawings:

Figure 1 is a front, elevation view showing my novel liquid cooler and dispensing device incorporated with the door of a refrigerator.

Figure 2 is a vertical, central, sectional view through the door taken on the line 2—2 of Figure 1, looking in the direction of the arrows.

Figure 2a is a fragmentary, horizontal, sectional view taken on the line 2a—2a of Figure 1 looking in the direction of the arrows.

Figure 3 is an enlarged fragmentary, detail, sectional view illustrating the connection of the dispensing valve with one of the dispensing jars.

Figure 4 is an enlarged, fragmentary, detail, sectional view illustrating the use of an adapter for permitting the dispensing of milk and the like from their original bottles.

Referring to the drawings in detail, wherein similar reference characters designate corresponding parts throughout the several views, the letter C generally indicates my novel liquid cooler and dispensing device incorporated with the door D of a refrigerator.

While in the drawings, for the purpose of illustration, I have shown the cooler and dispenser incorporated with a refrigerator door, it is to be understood that the cooler and dispenser can be built in a stationary wall.

The door D includes the inner metal or like

shell 5 and the outer metal or like shell 6 and these shells 5 and 6 are firmly united, and confined between the same is any preferred type of insulation 7.

During the stamping out of the inner shell 5 a transversely extending instruck cavity, pocket, or recess 8 is formed, the purpose of which will be later described. The outer shell 6 has formed therein during the stamping out thereof, an instruck pocket, cavity or recess 9, the purpose of which will also be later set forth. It is to be noted, however, that the pocket 9 can be of a less height than the pocket 8 and that the pocket 9 can be provided with a marginal flange or shoulder 10.

As is clearly shown in Figures 1 and 2 of the drawings, the pocket 9 is arranged directly below the pocket 8 and that the pocket 8 opens into the interior of the refrigerator, while the pocket 9 opens out through the outer face of the refrigerator.

The pocket 8 is adapted to receive a plurality of liquid dispensing jars 11 and these jars can be formed from any desired material, such as, glass or plastic. Each jar includes a depending neck 12 and a filling spout normally closed by a removable cap 13.

The pockets 8 and 9 are connected by spaced openings 14 and the necks of the bottles are insertable in said openings and preferably extend into the lower pocket 9. Sealing gaskets 15 can be utilized for fitting partly in said openings 14 and around the necks of the bottles to reduce breakage when the jars are initially placed in position and to prevent the flow of air between the pockets 8 and 9. The necks can be provided with outwardly extending, diametrically disposed pins 16.

A simple type of valve 17 is provided for each bottle neck and each valve can include a casing 18 having a vertical passageway 19 therethrough for the flow of liquid. One end of the casing is provided with a sleeve 20 for receiving a jar neck and this sleeve can have formed therein a bayonet slot 21 for receiving the pins 16. This provides a quick releasable connection between each valve and its neck. A rotatable valve plug 22 controls the flow of liquid through the valve casing and a handle 23 can be provided for rotating the plug.

Obviously, the flow of liquid is directly from the jar to the valve and there is no chance for liquid being trapped in the valve.

The jars 11 can be filled with the desired liquid by removing the caps 13 and one jar can be utilized for water, another jar for fruit juice, and so on.

As the cavity or pocket 8 opens into the interior of the refrigerator, the contents of the jars will be cooled by the air in the refrigerator and consequently by manipulating the valves, cool liquid can be readily had without the necessity of opening the refrigerator door. As the valves are arranged within the cavity 9 the same can be easily and conveniently manipulated from the exterior of the refrigerator.

The outer pocket 9 is normally sealed by a closure 24, which in the present instance is connected to the refrigerator by hinges 25. These hinges are of the knuckle type so that when the closure is in its open position, the same will be maintained in a horizontal plane to act as a serving shelf for drinking glasses. The closure can be provided with a marginal flange 26 for engaging the shoulders 10 around the cavity or pocket 9 and when the door is closed, the same is substantially flush with the outer face of the refrigerator.

Where it is desired to dispense milk directly from the milk bottles, an adapter 28 can be employed (see Figure 4). This adapter includes a resilient body or gasket 29 having a seat 30 for receiving the bead on the milk bottle neck and the body carries a cylindrical sleeve 31 which can be utilized for receiving the dispensing valve.

The jars 11 are somewhat firmly held in their operative position by the valves 17, but in order to insure the accidental displacement thereof by the slamming of the door, I can provide a holding rod 32 therefor. This holding rod 32 can extend across the jars and can be held in place by hooks 33 carried by the inner face of the door or wall of the refrigerator.

A spring 22' can be utilized for keeping the valve plug 22 snug and tight on its seat at all times.

The valve to be attached to the milk bottle adapter 28 is made small enough to go through its opening or port 14 from the inside of the door.

From the foregoing description, it can be seen that I have provided an exceptionally simple and novel means for incorporating a liquid dispensing and cooling device with a refrigerator, which will eliminate the continuous opening and closing of a refrigerator door and one in which all parts are concealed and protected from dust and dirt. Obviously my device will save from $\frac{1}{2}$ to 1 cubic foot of space in the refrigerator for other foods, which would ordinarily be occupied by bottles, etc.

Changes in details may be made without departing from the spirit or the scope of my invention, but what I claim as new is:

A refrigerator wall or door having an upper inwardly directed pocket formed in its inner face and a lower inwardly directed pocket formed in its outer face, said pockets being connected at spaced points by openings, removable liquid dispensing jars fitted in said upper pocket having necks extending into said openings, sealing gaskets fitted in said openings and surrounding said necks, detachable valves disposed in the lower pocket connected with said necks, a closure for completely sealing the lower pocket and hiding said valves from view, when said closure is in its closed position, and means for holding the closure at right angles to the outer face of said door when in its fully open position to provide a serving tray.
